UNITED STATES PATENT OFFICE.

HENRY L. REYNOLDS, OF JERSEY CITY, NEW JERSEY, ASSIGNOR TO THE LIDGERWOOD MANUFACTURING COMPANY, OF NEW YORK, N. Y., A CORPORATION.

EXCAVATING-BUCKET.

SPECIFICATION forming part of Letters Patent No. 747,480, dated December 22, 1903.

Application filed June 17, 1903. Serial No. 161,893. (No model.)

To all whom it may concern:

Be it known that I, HENRY L. REYNOLDS, a citizen of the United States, and a resident of Jersey City, Hudson county, New Jersey, have 5 invented certain new and useful Improvements in Excavating-Buckets, of which the following is a specification.

My invention relates to improvements in excavating or dredging buckets.

10 The object of my invention will be disclosed in the following specification and its scope will be defined by the claims terminating the same.

In the drawings accompanying herewith I 15 have shown my invention embodied in a form now preferred by me.

In the drawings, Figure 1 is a side elevation of my device, the closed position being shown in full lines and the open position being indicated diagrammatically by broken lines composed of dots and dashes which outline the buckets or scoops and indicate the center lines of the various levers and links. Fig. 2 is a central sectional elevation at right 25 angles to Fig. 1, showing one-half the device in elevation.

My device is of that type of excavating-buckets having two opposed scoops which are supported and operated by a system of levers 30 and links, so as to widely separate the scoops and then bring them together with a scraping action, so that in some materials it may loosen the material at the time of loading. With this latter object in view I have so designed the parts as to place the buckets or 35 scoops with their bottom surfaces in a substantially vertical plane when the scoops are at their extreme separation preliminary to loading and so that as the closing operation 40 is commenced the scoops will be rapidly tilted to a favorable digging or scraping angle and be then maintained approximately at this angle until completely closed. In order to secure this action, the "scoops" (by which term 45 I mean the lower bucket-like members which contain the material) are pivotally carried by hangers or levers, which in turn are pivoted at or near their upper ends so as to swing toward and from each other. The scoops are 50 controlled in their angular position by means

of mechanisms which are in turn controlled by the swinging of the hangers.

In the drawings, 1 represents the scoops, two of which are provided, said scoops preferably having a bottom and two sides, the front and rear ends being open. The scoops are carried by hangers 2, connected thereto by pivots 10, and these hangers are pivoted to each other or to a common pivot 3 near their upper ends. Four of these hangers are 60 employed, two for each scoop, the same being placed one at each side of a scoop. The common pivot 3 for the hangers is preferably a rod, which extends transversely of the bucket and connects the hangers of one side of the 65 bucket with the hangers at the other side of the bucket. These pivoted hangers by the degree of their separation control the location or separation of the scoops, while the angular position of the scoops is controlled or 70 modified by other mechanisms, which while separate from the hangers are controlled in their movements by connection with said hangers. These mechanisms I have termed "scoop-controlling" or "position-controlling" 75 to distinguish them from the other or scoop carrying and swinging mechanisms—that is, the hangers 2.

Links 15 are connected with the scoops rearwardly from the point of connection of the 80 hangers thereto. These links are adapted to act under the influence of the position-controlling mechanism to tilt or rock the scoops upon their pivots 10, so as to secure the angular position desired—such, for instance, 85 as has been hereinbefore specified. I have shown the links 15 as pivoted together at their upper ends by means of a pin 32, such pin being upon the central line of the bucket. By the term "bucket" as herein used I refer to 90 the device as a whole and not to the members 1, which are herein referred to as "scoops."

If the pin 32 is maintained on the central line of the bucket while the two parts are separated by the swinging of the hangers, and 95 if at the same time this pin be moved downwardly upon such center line as the hangers swing outwardly, the scoops will during the major part of their outward movement be maintained approximately in the same angu- 100

lar position as when closed, and during the latter part of the outward swinging movement of the hangers the buckets will be rapidly rocked into the vertical position shown by the broken lines in Fig. 1. In order to secure this action, I have connected the pivot 32 by means of links 4, which, in effect, form a toggle with the outer ends of extensions 2^a of the hangers beyond their pivot 3. These extensions 10 lie upon the opposite sides of the pivot 32, from the hangers of which they form a part—that is, the extension 2^a, which lies at the right of the center line of the bucket, is a part of the hanger 2, which lies at the left of the center line of the bucket, and vice versa. I have herein shown these extensions as being substantially horizontal in the closed position of the bucket. The exact angle made by these extensions, as well as by other parts of 15 the device, and also the relative lengths of the parts and locations of the pivots, may be widely varied without changing the essential character of the invention. By varying these parts the action of the device may be widely 20 changed.

As the hangers are swung outwardly the extensions 2^a swing downwardly, which carries the toggle-links 4 downwardly and at the same time closes the toggle, which tends to 25 carry the central pivot thereof, 32, downwardly at an increased rate. The position of the parts when the bucket is opened is shown by the broken lines, composed of alternate dots and dashes, in Fig. 1. The first action 30 of the toggle-links 4 upon the scoops 1 is to depress the outer ends thereof; but this depression is counteracted somewhat by the fact that the links 15 are primarily at a considerable angle relative to the direction of the 35 hangers 2. As the hangers near the outer portion of their swing the links 15 pass the horizontal position and farther movement downward draws inward the outer end of the bucket. At the same time the inner ends of 40 the buckets continue moving outwardly, which results in a rapid rocking action upon the bucket, which quickly turns it into the 45 vertical position.

The means provided for opening or swinging outward the two parts of the buckets consists of toggle-links 8, which are pivoted to the hangers at 30 and have a common or center pivot 31. The pivots 30 are removed laterally from the center line of the bucket, so 50 that if the common pivot 31 be moved upwardly the hangers will be swung outward or separated. This central pivot 31 is moved upwardly by means of an opening-rope, which is connected thereto. This opening-rope 55 might be connected directly with the pivot 31, but in some cases such a connection would not provide a sufficient opening power. In such event this power may be increased by the means which are clearly shown in Fig. 2. As 60 therein shown, a single opening-rope 16 is located centrally of the bucket and at its end is

branched so as to provide two end sections 6. The lower or central pivot for the toggles is in the form of a transverse shaft 31, which connects the two toggles at opposite sides of 65 the bucket. Upon this shaft are mounted two pulleys 9, which lie substantially in the central transverse plane of the bucket. The two branches 6 of the opening-rope each pass about one of the pulleys 9 and then upward. 70 Each of these branches may then be directly connected with the transverse shaft 3, which forms the pivot for the hangers, or, as is herein shown, they may be passed around pulleys 19, carried by said shaft, and thence downwardly and be attached to the shaft 31. It is 75 obvious that by pulling upon the opening-rope 16 the shaft 31 will be powerfully drawn upward or toward the shaft 3, which will open out the toggle-links 8, and thus separate the 80 two parts of the bucket.

The closing means shown consist of pulleys 7, mounted upon the hangers as near to their lower ends as convenient, about which extend the closing-ropes 70, one rope being used 85 at each side of the bucket. The power of these closing-ropes may be increased by increasing the number of pulleys 7. I have herein shown two such pulleys upon each hanger. One end of the closing-rope is secured to one of the hangers by any suitable means and thence passes about the pulleys 7 and thence upward through a guide or over a pulley 17, located adjacent to the pivot of 90 the hangers.

I prefer that the rods 30, by which the opening links or toggles 8 are pivoted to the hangers, be located at such a distance from the pivot 3 of said hangers that the extensions 2^a of said hangers may swing within said rods 95 30. In some cases there may be no necessity for such clearance. The toggle-links 4, which together with the extensions 2^a and links 15 constitute what I have called the "scoop-controlling" or "position-controlling" devices, 100 are preferably placed outside of the plane of the opening links or toggles 8, so that their centers may freely pass.

I do not wish to be understood as limiting myself to the exact construction or operation 105 of parts herein shown and described, but to claim any construction which falls within the scope of the claims terminating this specification.

What I claim, and desire to secure by Letters Patent, is—

1. An excavating-bucket comprising two opposed scoops, swinging hangers pivoted to the scoops, and means controlled by the conjoint action of both of said hangers to control 115 the angular position of the scoops.
2. An excavating-bucket comprising two opposed scoops, swinging hangers pivoted to the scoops, and means comprising toggle-levers pivoted to said hangers for controlling 125 the angular position of the scoops.
3. An excavating-bucket comprising two

- opposed scoops, swinging hangers pivoted to said scoops, links pivoted to the scoops and to each other, and means connected with and actuated by the said hangers for moving the common pivot of said links vertically as the main levers are swung to open or close the scoops.
4. An excavating-bucket comprising two opposed scoops, swinging main levers or hangers pivoted to the scoops, links pivoted to the scoops outwardly from the pivotal connections of the hangers thereto, and means connected with said hangers and actuated by the swinging thereof to move the other ends of said links vertically as the hangers open or close.
5. An excavating-bucket comprising two opposed scoops, swinging hangers pivoted thereto, links pivoted to the scoops and means controlled by the swinging of said hangers to move the other ends of said links downwardly as the hangers swing apart.
6. An excavating-bucket comprising two opposed scoops, swinging hangers pivoted thereto, links pivoted to the scoops, and means controlled by the swinging of the hangers to thereby move the other ends of the said links downwardly as the hangers swing apart upon the center line of the device.
7. An excavating-bucket comprising two opposed scoops, swinging hangers pivoted thereto, links pivoted to the scoops and to each other and means controlled by the hangers for maintaining the common pivot of said links upon the center line of the device and for shifting said common pivot downwardly as the hangers swing apart.
8. An excavating-bucket comprising two opposed scoops, swinging hangers pivoted thereto, links pivoted to the scoops and to each other, and other links connecting the common pivot of said first links with opposite hangers.
9. An excavating-bucket comprising two opposed scoops, swinging hangers pivoted thereto and to each other and having an extension beyond their common pivot, links pivoted to the scoops, and other links connecting said first links with the said extensions of the hangers.
10. An excavating-bucket comprising two opposed scoops, swinging hangers pivoted thereto and to a common pivot and having extensions beyond said common pivot, links pivoted to the scoops and to each other, and other links pivoted to the common pivot of the first links and to the said extensions of the hangers.
11. An excavating-bucket comprising two opposed scoops, swinging hangers pivoted to the scoops and to each other, links pivoted to the scoops and to each other, and means connected with both hangers and acting upon said last links to control the position of the buckets.
12. An excavating-bucket comprising two opposed scoops, swinging hangers pivoted to the scoops, and independent opening and position-controlling links connected with said hangers.
13. An excavating-bucket comprising two opposed scoops, swinging hangers pivoted to the scoops, and a plurality of connected links connecting each scoop with the hangers, said links for the same side of opposite scoops all having a common pivot.
14. An excavating-bucket comprising two opposed scoops, swinging hangers pivoted to the scoops, opening toggle-links pivoted to the hangers, position-controlling links connected with the hangers, and other links connecting said position-controlling links with the scoops.
15. An excavating-bucket comprising two opposed scoops, swinging hangers pivoted to the scoops, opening-links connected with the hangers and with each other to form a toggle, position-controlling links connected with the hangers and with each other to form a toggle, said two toggles working oppositely, and links connecting the position-controlling toggle with each scoop.
16. An excavating-bucket comprising two opposed scoops, four hangers pivoted thereto one at each side of each scoop, a shaft forming a common pivot for the upper ends of said hangers, opening-links pivoted to the hangers and to each other to form a toggle at each side of the bucket, a shaft forming a common pivot for both of said opening-toggles, pulleys carried by said shaft, and an opening-rope passing about said pulleys and upward to the upper shaft.
17. An excavating-bucket comprising two opposed scoops, four hangers pivoted thereto one at each side of each scoop, a shaft forming a common pivot for the upper ends of said hangers, opening-links pivoted to the hangers and to each other to form a toggle at each side of the bucket, a shaft forming a common pivot for both of said opening-toggles, and an opening-rope extending in a plurality of runs between said two shafts to form a power device for opening the bucket.
18. An excavating-bucket comprising two opposed scoops, four hangers pivoted thereto one at each side of each scoop, a shaft forming a common pivot for the upper ends of said hangers, opening-links pivoted to the hangers and to each other to form a toggle at each side of the bucket, a shaft forming a common pivot for both of said opening-toggles, and a single central opening-rope branching and each branch extending in a plurality of runs between said two shafts to form a power device for opening the rope, one branch being at each side of the center of the bucket.
19. An opening means for buckets having two pivoted halves, comprising toggle-links pivoted to each half upon both sides of the bucket, upper and lower transverse shafts

forming respectively pivots for the buckets and for said toggles, and an opening-rope and pulleys therefor secured to said shafts and leading said rope in a plurality of runs between said shafts and in a plane transverse of the bucket.

20. An excavating-bucket comprising two opposed scoops, hangers pivoted to said scoops, said hangers being pivoted near their upper ends and having extensions beyond said pivots, position-controlling means for the scoops operated from said extensions, transverse rods connecting the hangers upon opposite sides of the scoops at a distance permitting the hanger extensions to swing within them, and opening toggle-links pivoted upon said transverse rods.

21. An excavating-bucket comprising pivoted hangers, opposed scoops carried by said hangers, pulleys carried by said hangers, a closing-rope passing about said pulleys and extending between the hangers, opening tog-

gle-links connected with the hangers upon both sides of the bucket, a transverse shaft connecting the central pivot of both toggles, and an opening-rope and pulleys therefor carried by said shaft said rope extending in a plurality of runs between said shaft and the upper part of the bucket and lying in a plane transverse to the bucket.

22. An excavating-bucket comprising two opposed scoops, swinging hangers pivoted to the scoops, means for applying power to said hangers to open and close them, and means actuated from and by the conjoint action of the hangers of both scoops to control the angular position of the scoops.

In testimony whereof I have hereunto affixed my signature, this 15th day of June, 1903, in the presence of two witnesses.

HENRY L. REYNOLDS.
